UNITED STATES PATENT OFFICE.

GEORGE JACKSON, JR., OF HOHOKUS, NEW JERSEY.

RAILWAY SIGNAL APPARATUS.

1,100,243.

Specification of Letters Patent. Patented June 16, 1914.

Application filed July 11, 1913. Serial No. 778,511.

To all whom it may concern:

Be it known that I, GEORGE JACKSON, Jr., a citizen of the United States, residing at Hohokus, in the county of Bergen and State 5 of New Jersey, have invented certain new and useful Improvements in Railway Signal Apparatus, of which the following is a specification.

This invention relates to automatic signal 10 apparatus, and it has for its object to provide a simple, easily installed, inexpensive and reliable apparatus of this kind designed especially for use in automatically signifying the approach of a car or train to 15 a crossing.

As herein shown and described my invention has been developed for use particularly in connection with single-track railway systems in which the traffic moves both ways, 20 but it will be understood that in certain respects the invention, or parts thereof, may be applied to double track railways. In the adaptation shown and described there are provided, with the signal and a suitable energy source, two signal-circuit establishing 25 contacts arranged at suitable distances from and on opposite sides of the crossing and between them, as at or near the crossing, a signal-circuit-disestablishing contact; each 30 of the first two contacts on acting causes the energizing of a magnet whose armature is a switch that on being moved by the magnet is held in a position to maintain the signal in operation for a suitable length of time, 35 and in order that after a car, in passing one of the signal-circuit-establishing contacts and then the signal-circuit-disestablishing contact, has first set and later terminated the signal it may not again set the signal on 40 reaching the other or "distant" signal-circuit-establishing contact, the latter is protected by means for neutralizing said magnet, to wit, by a contact that closes a circuit for holding the switch out of the influence 45 of said magnet, the latter contact being interposed between the signal-circuit-disestablishing contact and the "distant" signal-circuit-establishing contact; finally, relatively beyond the "distant" signal-circuit-establishing contact is placed another contact that thereupon neutralizes said means, to wit, by closing a circuit for breaking the last-named circuit and restoring the parts to *statu quo*. In this adaptation, further, 50 the holding of the switch in the first instance in the position to maintain the sig-

nal in operation and in the second instance in the position out of the influence of the magnet first above-mentioned is accomplished by a magnet whose circuit the 60 switch (its own armature), by contacting with its core, closes. These two (the first and last-mentioned magnets) I may form as one mechanical structure, there being two windings for a single core.

In said drawings, Figure 1 is an isometric view showing my invention applied to an electric railway system and Fig. 2 is a diagram of the improved apparatus, while Fig. 3 is a diagrammatic view of a part of the 70 apparatus, illustrating the above-mentioned modification thereof.

In the drawings, *a* is a railway track and *b* an intersecting street or the like where it is desired to signify the approach of a car 75 or train over the railway. The source of current for operating my apparatus in the present instance is afforded by conductors including the "feeder" *c* and the trolley wire *d*, supported by poles *e* in the usual 80 manner.

f is a set of lamps and *g* an electric bell. Either or both or any other suitable device may be employed as the signal of the apparatus.

At a suitable distance each side of the crossing formed by the intersection of the track *a* and road or street *b* are the contacts 1, 2 and 3, and at or near the crossing the contact 4, such contacts being conducting 90 devices of suitable form and arranged in such proximity to the trolley wire *d* that the intervening space between any of them and the wire will be electrically bridged by the trolley wheel *y* of a passing car.

From the feeder *c* extends a conductor *h* including a switch *A* for closing the circuit via this conductor and either of its branches *h' h''* to ground. Branches *h' h''* respectively include the cores and windings of 100 magnets *B' B''*, normally closed switches *C' C''* and the signal *f*, *g* and a fuse and snap switch *x*.

From the contacts 2 2 extend the branches *i' i''* of a conductor *i* which includes the 105 magnet *D'* and may be grounded by being connected with branch *h''* between switch *C''* and *x*; and from the contacts 1 1 extend the branches *j' j''* of a conductor *j* including the magnet *D''* and connected with 110 branch *h''* between switch *C''* and *x*.

From the contacts 3 3 extend the branches

k' k' of a conductor *k* and from the contact 4 a conductor *l*, the conductors *k* and *l* respectively including the magnets *E''* and *E'* and respectively connected with conductor *j*, 5 between *D''* and *h''*, and with conductor *i*, between *D'* and *h''*.

The switch *A* is pivoted and normally hangs pendent out of contact with either of magnets *D'* and *B'* on the one hand, or magnets *D''* and *B''* on the other, it constituting the armature of all these magnets, preferably by arranging the acting ends of the cores of each pair (*D'* and *B'*, or *D''* and *B''*) in a radius from the pivot of movement 10 of switch *A*. The switches *C'*, *C''* are pivoted and are normally held closed by gravity. These are the preferred conditions for the sake of simplicity and convenience, but they may be varied in many other ways 15 without departure from the invention. 20

Operation: Assuming the moving parts to be in the position shown in Fig. 2, on the trolley wheel *y* of a car approaching the crossing from the left bridging left-hand contact 3 and the trolley wire *d* nothing would occur but the momentary and idle opening of the switch *C''* due to the energizing of magnet *E''*. On left hand contact 2 and the trolley wire being bridged the current will pass through *i'*, *i*, *D'*, *h''* to ground, energizing *D'*, which will attract switch *A*; switch *A* will then close the circuit between *h* and *B'* which (the wheel *y* now having passed beyond 2) will hold *A* in contact with 30 itself (*B'*), the current passing via *h'*, *C'*, *h'* and the signal to ground, operating the signal. On the wheel now engaging contact 3 the closing of the circuit containing magnet *D''* (to wit, through *j*, *D''*, *R*, *j*, *h''*, *x* to 35 ground) will be ineffectual to cause said magnet to move switch *A*, because the latter is already held by magnet *B'*. The wheel *y* now passing on to and closing the circuit between 4 and the trolley wire, so that current flows via *l*, *E'*, *i'* and *h''* to ground, *E'* is energized, opening switch *C'* and so breaking the signal circuit, disestablishing the signal and deenergizing magnet *B'*, so that the switch falls away to its open position. 40 Right-hand contact 1 is now reached by wheel *y* and the latter bridging the same and the trolley wire the current flows from 1, via *j'*, *j*, *D''*, *h''* to ground, energizing *D''*, which draws switch *A* to the left, *i. e.*, into 45 circuit-closing contact with *B''* so that after *y* leaves contact *l* the current, via *h*, *A*, *B''*, *h''*, *C''*, *h''* to ground, will cause *B''* to hold the switch *A* from being moved to the right when the circuit is next closed at 2 by the 50 trolley wheel, via *i'*, *i*, *D'*, *i*, *h''* to ground. Finally, right hand contact 3 is reached by the wheel *y*, the current flowing via *h'*, *h*, *E''*, *j*, *h''* to ground, *E''* momentarily opening switch *C''* and thereby deenergizing *B''*, which results in the apparatus being 55

restored to its normal conditions. It will be obvious that the results are the same when the trolley wheel moves from right to left past the several contacts.

The disposition and relative strengths of the magnets *D'* *D''* *B'* *B''* are such that when *B''* is holding the switch in the signal-circuit-closing position *D''* is powerless to withdraw it therefrom; and when *B''* is holding the switch to the left in Fig. 2 *D'* 70 75 is powerless to draw it out of the control thereof.

It will thus be seen that in accordance with this invention the vehicle on engagement with one of the devices 2 causes electro-magnetic means including said devices to close the signal-containing circuit; that thereupon means, operated by the vehicle after each closing of said circuit (upon its engagement with the device 4), causes the 80 85 opening of the said circuit; and that finally other means, operated by the vehicle before its next engagement with one of said devices 2 (upon its engagement with one of the devices 1) operates to neutralize said electro-magnetic means. 90

In Fig. 3 there is shown a construction of magnet in which each pair of magnets *D'* and *B'* and *D''* and *B''* may be compounded as one, having a common core *z*. 95 The wire *h'* (or *h''* as the case may be), having the core as its terminal is wound around the same as shown and then proceeds to ground, including in transit the same elements as are shown in Fig. 2; the wire *i* (or 100 *j*, as the case may be) extends from the contact 2 and, including the same elements as are shown in Fig. 2, is wound around the core, finally proceeding to ground.

Resistances *R* are placed in the conductors *h''* and *j*, one between *x* and the point where *i* joins *h''* and the other in *j* between where *j* joins *h''* and where *h* joins *j*.

Having thus fully described my invention, what I claim as new and desire to secure by Letters Patent is:—

1. In combination, a railway, a vehicle movable thereover and having a circuit-closer, a source of current having a conductor extending along the railway, a grounded signal-containing conductor connected with said source and including a magnet and a normally open switch constituting the armature of the magnet and also including a normally closed switch, another grounded conductor containing a magnet having the first switch as its armature and having a pair of contacts in circuit-closer-bridging proximity to, and spaced from each other longitudinally of, said source-conductor, a third grounded conductor also containing a magnet having the second switch as its armature and having a contact between the first two contacts in circuit-closer-bridging proximity to said source- 115 120 125 130

conductor, and means, operated by said circuit-closer after bridging the last-named contact and said source-conductor, for moving the first-named switch out of the influence of the second-named magnet, substantially as described.

2. In combination, a railway, a vehicle movable thereover and having a circuit-closer, a source of current having a conductor extending along the railway, a grounded signal-containing conductor connected with said source and including a magnet and a normally open switch constituting the armature of the magnet and also including a normally closed switch, another grounded conductor containing a magnet having the first switch as its armature and having a pair of contacts in circuit-closer-bridging proximity to, and spaced from each other longitudinally of, said source-conductor, a third grounded conductor also containing a magnet having the second switch as its armature and having a contact between the first two contacts in circuit-closer-bridging proximity to said source-conductor, another magnet having said first-named switch as its armature and operating thereon reversely to the first-named magnet, another grounded conductor having the core of the last-named magnet as its terminal and containing a normally closed switch, another grounded conductor having a pair of contacts arranged between the first pair of contacts and each side of the contact of the third grounded conductor and in circuit-closer-bridging proximity to said source conductor and also including a magnet having said first-named switch as its armature and operating thereon reversely to the first-named magnet, and another grounded conductor having a pair of contacts arranged both sides of the first pair of contacts and in circuit-closer-bridging proximity to said source-conductor and including a magnet having the last-named switch as its armature, substantially as described.

3. In combination, a railway, a vehicle movable thereover and having a circuit-closer, a source of current having a conductor extending along the railway, a grounded signal-containing conductor connected with said source and including a magnet and a normally open switch constituting the arm-

ture of the magnet and also including a normally closed switch, another grounded conductor containing a magnet having the first switch as its armature and having a pair of contacts in circuit-closer-bridging proximity to, and spaced from each other longitudinally of, said source-conductor, a third grounded conductor also containing a magnet having the second switch as its armature and having a contact between the first two contacts in circuit-closer-bridging proximity to said source-conductor, another magnet having said first-named switch as its armature and operating thereon reversely to the first-named magnet, another grounded conductor having the core of the last-named magnet as its terminal and containing a normally closed switch, another grounded conductor having a pair of contacts arranged between the first pair of contacts and each side of the contact of the third grounded conductor and in circuit-closer-bridging proximity to said source conductor and also including a magnet having said first-named switch as its armature and operating thereon reversely to the first-named magnet, and another grounded conductor having a pair of contacts arranged both sides of the first pair of contacts and in circuit-closer-bridging proximity to said source-conductor and including a magnet having the last-named switch as its armature, substantially as described.

In testimony whereof I affix my signature in presence of two witnesses.

GEORGE JACKSON, JR.
